FIG. 1 is a perspective view of a combined shampoo couch and cabinet unit showing my new design;

FIG. 2 is a side elevational view thereof; and

FIG. 3 is an end elevational view thereof.

The design is characterized by the combination on the couch disclosed of the elevated head portion and the lower foot portion in association with the cushion top and paired door arrangement being parallel to the base, all as shown.

I claim:

The ornamental design for a combined shampoo couch and cabinet unit, as shown and described.
